PHOTOFASH LAMP MOUNTING BRACKET

Thomas L. Eichelberger, R.R. 2,
Sidney, Ohio 45365

Filed Oct. 28, 1968, Ser. No. 14,201
Term of patent 14 years

Int. Cl. D16—07

U.S. Cl. D61—1

FIG-1

FIG-6

FIG. 1 is a perspective view of my photoflash lamp mounting bracket showing my new design;

FIG. 2 is a perspective view of the rear thereof;

FIG. 3 is a side view thereof;

FIG. 4 is a front view thereof;

FIG. 5 is a top view thereof; and

FIG. 6 is a bottom view thereof.

I claim:

An ornamental design for a photoflash lamp mounting bracket, substantially as shown.
